CHARLES EDGE.

UNITED STATES PATENT OFFICE.

CHARLES EDGE, OF NEWARK, NEW JERSEY, ASSIGNEE TO HARRIET EDGE,
OF SAME PLACE.

DESIGN FOR AN ORNAMENTAL CHAIN.

SPECIFICATION forming part of Design No. 15,389, dated September 9, 1884.

Application filed October 16, 1883. Term of patent 14 years.

To all whom it may concern:

Be it known that I, CHARLES EDGE, of Newark, in the county of Essex and State of New Jersey, have invented a new and original Design for a Chain, of which the following is a specification, reference being had to the accompanying photographic illustration, making a part of this specification.

This invention relates to a new and ornamental configuration for a chain.

The chain A shown in the accompanying photograph contains a row of loops, *a a*, along one edge and a row of loops, *b*, along the op-

posite edge. Between these loops are posts *d d*, each post being of double strands, that is, overlap one another three times in each post, thereby producing the peculiar effect shown.

I claim—

The design for a chain, the same consisting of the rows of loops *a b* and the posts *d*, as shown.

CHARLES EDGE.
